SUCTION AND CLEANING APPARATUS

Johan Edvin Jonsson, Stockholm, Ragnar Wilhelm Larsson, Appelviken, and Anders Johan Emil Rylander, Stockholm, Sweden

Application February 14, 1934, Serial No. 711,266
In Sweden April 29, 1933

7 Claims. (Cl. 15—15)

The present invention relates to a suction apparatus or device, which operates with compressed air or other compressed gaseous medium and in which the compressed air et cetera is pressed through a nozzle past an opening through which the medium intended for the suction by the compressed air is sucked into or is entrained into an exhaust pipe, which is located beyond the opening when seen in the direction of flow.

10 The object of the present invention is to provide an apparatus for vacuum cleaners especially suitable for automobiles, factories, motor boats, for sucking water, as a ventilator, etc. The apparatus may also be used for vacuum cleaning in factory localities or the like, in which compressed air is at disposal. Moreover, the apparatus is meant to be used as an air cleaner in localities of the last mentioned kind, in which compressed air or other compressed medium may be obtained, or in automobiles, omnibuses or the like, in which the exhaust gases of the motor may be used as compressed medium. Further, the apparatus may be used for sucking water, for example for emptying a boat or the like.

15 Other characteristics of the invention will be seen from the detailed description set forth below.

The accompanying drawings show embodiments of the invention. Figures 1 to 8 show examples of the invention as applied to a vacuum cleaner,

Figure 1 is a side view of the apparatus,

Figure 2 is a plan view of the apparatus,

Figure 3 is a section taken on line III—III of Figure 2,

Figures 4, 4a, 5 show the tap or the like provided in the air distributing box, when seen from above, in section and from behind respectively in an embodiment differing a little from the one shown in Figure 3,

Figure 6 is a perspective view of one embodiment of the tap,

Fig. 6a is a cross section on line VIa—VIa of Fig. 6;

Fig. 6b shows the manner of securing this embodiment in position,

Figs. 7 and 8 show a further embodiment of the tap,

Figures 9 and 10 show details of an air cleaning arrangement according to the invention, especially intended for omnibuses or the like, Figure 10 being a section along line X—X of Figure 9.

In the embodiment shown, Figs. 1 to 8, see especially Figs. 1, 2 and 6a, numeral 1 indicates the

supply conduit or pipe for the compressed air (medium), which by means of a screw or bayonet connection, indicated at 41, is adapted to be connected to a conduit from the source of compressed air.

5 Numeral 2 indicates the case of the apparatus, which moreover forms an exhaust conduit and has a canal 3, into which the atmospheric air together with dust particles et cetera entrained by the compressed air is introduced through the opening 9 and moved on to the dust collector 10, which may be of any suitable material and may have any shape and by means of a bayonet catch, indicated at 11, or in other suitable manner is detachably connected to the case 2. The said case is provided with a projection 4, into which the pipe 1 is screwed and united with the connecting pipe 5. The pipe 1 is held in its position by a stirrup 6 or the like, one leg of which is rigidly united with the case 2, the other leg being loose so that by means of the screw 7 the pipe may be clamped and loosened respectively from its position. Other arrangements for holding the pipe in its position or for securing it to the casing may be used. Numeral 8 indicates a handle of wood or the like.

The case 2 has a cap-like casing 12, which is formed to an injection nozzle and which may have any shape but in the embodiment of the invention is cylindrical and has the same width as the rest of the case. Through the opening 14 (Figures 3 and 7) the compressed air enters the space in the casing, which has a circular cross section, and in the said space there is, through an opening in either end of the casing 12, detachably disposed a substantially cylindrical guide body valve 18, or tap. In the embodiment the said body is formed as a rotary slide valve or the like, the end portions 20 of which have the same diameter as the inner width of the space of the casing. As may be seen, the said guide body extends perpendicularly to the compressed air piping and to its connecting pipe 5 and the exhaust conduit 2. Between the body and the wall of the casing in all embodiments there is formed, when seen in the direction of flow, a narrowing passage 15' for the compressed air, the mouth 15 of which forms a narrow slit located at the edge 16 of a suction opening 9 in the casing 2. By means of the guide body or tap 18 the compressed air is conducted, spread and distributed uniformly towards the outlet 15 as will be more particularly explained in the following. The edge 16 is inclined toward the guide member so that the compressed air rushing out through the

mouth 15 entraining atmospheric air and dust particles et cetera, substantially is led right into the exhaust canal 3. The sloped face, at 17, has for its object to prevent friction with the wall of the apparatus, and to prevent the formation of eddies and sudden reduction in speed.

The face 23, Figs. 4 to 5, and 7 and 8 and the corresponding face in Figs. 3, 6 and 6a which is opposite the wall of the casing at the edge 16 is so sloped that on turning the top the size of the mouth (opening slot) 15 may be controlled. For actuating the guide body for turning and clamping the same, one end of it, according to Figs. 1, 4 and 5, preferably is provided with a portion 18 indicated at 18' for engaging a tool, or may be arranged in some other suitable manner. The taps according to Figs. 4 and 5 may also be arranged so as not to be turned.

So it is shown as to tap 18 according to Figure 6b, in which one end portion of it is preferably provided with a projection or catch 31, which, when the tap is being introduced engages a recess 32, which corresponds to the said catch and is provided in the wall of the casing 12. For its operation the tap is preferably provided with a grooved button 33. If another size of the mouth 15 is desired, the tap is taken out and another tap is inserted, which has the suitable dimension.

In Figs. 3 to 6b, a solid and in Figs. 7 and 8 a tubular guide body is shown.

According to Figs. 3 to 6 the guide body on its side opposite the inlet opening 14 is provided with a recess 19 of a size approximately corresponding to that of the opening. The said recess opens into a space or a canal 13 formed between the wall of the casing 12 and the guide body, the said space 13 merging into the mouth 15 by way of the passage 15'. The face of the guide body between the end portions 20, which limits the said space, 40 is shaped in various ways in connection to the recess 19.

In Figs. 4, 4a and 5, the thickness of the rear of the guide body, when seen in the direction, in which the compressed air enters, is reduced so as to form a plane surface 34, into which the recess merges by means of faces 36, which are continuously curved towards both sides, in order that the conducting of the air into the space 13 shall take place as smoothly as possible. The said sloped face 34 merges into a cut-away face 23 (Fig. 5).

According to Fig. 3 the rear guiding surface 35, into which the curved faces 36 merge, corresponding to the faces in Figs. 4 to 5, is spiral or curvilinear in all cross sections through the tap.

In the above mentioned manner the space 13, when seen in cross section, will get a so to speak wedge-like shape or increases substantially continuously toward the passage 15' or the mouth 15, and through the space the air is spread over the whole mouth 15, the latter having the same area as the opening 14. No sharp edges or turns exist, which could produce eddies or changes in speed of the air.

According to Figs. 6 to 6b the guide body 48 has a slightly conical shape and the casing 12 is shaped correspondingly so as to facilitate the removal and the inserting of the tap. The rear guiding surface is formed by a reduced (cut away) portion 37' between the bounding edges 70 37, which extend from the recess 19 in a bow or spirally towards both sides and which extend up to and somewhat past the part of the guide body, which is opposite the edge 16. The degree of reduction of the body for forming the face 37' decreases, when seen in cross section, continu-

ously to the same extent as the extension of the face in axial direction increases so that the depth of the space 13 between the guide body and the wall of the casing 12 for the passing compressing air decreases successively from the recess 19 toward the mouth 15 at the same time as the width is increased and subsequently the cross section of the space is the same in all axial sections.

According to Figs. 7 and 8 the guide body or tap 58 is shaped as a cylindrical tube with closed ends, the compressed air entering the said tube through an inlet opening 21 and leaving it through an outlet opening 22 after spreading and being led into the narrowed passage 15' between the walls of the tube and the casing 12 respectively. Nor in this case is the air subjected to any eddying movements et cetera. This tube is not, of course, necessarily cylindrical.

According to the embodiments in Figs. 4, 4a and 5, the face 23 of the guide body or tap 18 which is opposite the wall of the casing at the edge 16 is so sloped that on turning the tap the size of the opening 15 may be controlled. This is also true of the construction shown in Figs. 7 and 8. This enables the operator to vary the suction effect desired for each special case and by widening the mouth opening to remove impurities et cetera, which may have assembled in the narrowed passage during the working and which dam up the compressed air, and which, when the compressed air has been obtained for example from a cylinder of a motor, may occur in considerable quantities. Of course, such cleaning is effected most effectively and most suitably by removing the guide body, which may be done in all embodiments, it being easier than to reach the interior of the casing 12.

In the apparatus shown in Figures 1 and 2 the connecting pipe, the distributing casing and the exhaust case are preferably made in one piece, for instance by means of press casting. Next to the casing the under wall should preferably extend diverging from the upper one, as is shown in Figure 1, so as to facilitate the handling of the apparatus during the cleaning. The apparatus shown in the example is especially intended for cleaning automobiles with the use of compressed air obtained from the motor, and quite naturally is shaped as a handy, relatively small apparatus for manual use. If the apparatus is made larger, for example in order to be used in factories and the like, it is preferably provided with wheels, on which it is running during the work. Of course the supply pipe 1, 5 may, instead of being disposed substantially parallel to and above the exhaust casing be disposed in another suitable way.

Figs. 9 and 10 show a suitable application of the apparatus for ventilating purposes, especially for use in omnibuses or the like using the exhaust gases from the motor as a medium for obtaining injection effect. Numeral 26 indicates the conduit associated with the exhaust pipe, 25 indicates a conduit or funnel associated with the air in the room and through which the air is entrained by the rushing exhaust gases and by the same is introduced into the outlet conduit 27, which opens into the open air. Like in the previous example the tube 26 merges into a cylindrical casing 28, which preferably is made to act as an injection nozzle and has a larger width than the tube. The guiding body and the rotary slide valve 29 is applied in the said tube and provided with a cylindrical face 38 and a cutaway face 39 of elliptical shape, one side of which merges into the

circular face by means of a spiral-shaped curve 40, between which last-mentioned surface and the wall of the casing the narrowed passage 15' is formed. The slide is turnably disposed (the arrangements for actuating the same are not shown) and when it assumes the position shown in full lines the gases rush through the mouth 30 of the slit-shaped nozzle, by which a strong suction effect is exerted on the air in the conduit 25. As 10 the slide is moved to the position shown in dashed lines the exhaust gases are led past the slide along its right elliptical face between the end portions 29 provoking a suction action in the conduit 25, although it is weaker. The casing 28 15 and the outlet opening thereof as well as the connections of the various conduits to the casing may of course be varied as to shapes and positions relatively to one another.

It is clear that independent of the specific 20 cylindrical tap used it may be turnable or not by use of the different connections to the casing shown.

Further modifications of the devices shown may 25 of course be thought of without departing from the spirit of the invention.

Having now described our invention, what we claim as new and desire to secure by Letters Patent is:

1. A suction apparatus for vacuum cleaning operating with a fluid medium under pressure comprising a casing having an inlet and an outlet dust-collecting conduit, means leading the fluid medium to the casing through said inlet, a dust-entraining aperture in said dust-collecting conduit, a member forming a combined guide and valve adjustably mounted in said casing the rear edge of the dust-entraining aperture being inwardly inclined toward the said member, said member forming a guide for the fluid from the 30 inlet of the casing to the outlet of the casing and forming a narrow ejector slit therebetween opening directly into the dust-collecting conduit whereby the compressed medium is guided through the slit past the said aperture directly 35 into the dust-collecting conduit.

2. The device according to claim 1 in which the combined guide and valve member is a solid tap 40 rotatably mounted and has a surface cut away toward the inwardly inclined edge of the dust-entraining aperture whereby the width of the 45 ejector slit may be varied.

3. The device according to claim 1 wherein the combined guiding and valve member is a solid tap 50 rotatably adjustably mounted and has a smooth guiding surface cut away toward the inwardly inclined edge of the aperture the radius of said surface increasing continuously from said inlet toward said edge and the surrounding casing wall has a substantially continuously curved internal 55 surface from the inlet to the outlet whereby sharp angles are avoided in the passage for the compressed fluid medium and the size of the ejector slit may be varied.

4. The device according to claim 1 wherein the combined guiding and valve member is a solid tap 60 and has a smooth guiding surface of curvilinear cross-section and is cut away toward the inwardly inclined edge of the aperture, the radius of said surface increasing continuously from said 65 inlet toward said edge and the surrounding casing wall has a substantially continuously curved internal surface from the inlet to the outlet so that a canal is formed the cross-section of which decreases toward the dust entraining aperture.

5. A suction apparatus operating with com-

pressed air or other fluid medium under pressure and more particularly intended for vacuum cleaners, the said apparatus comprising a case with an inlet opening of substantial width and a dust collecting canal leading therefrom for the air, an opening in the said canal past which the air is led and through which dust particles et cetera are sucked and entrained into said dust collecting canal, a guiding valve member provided in the case between the last mentioned opening and the inlet opening for conducting and distributing the air from the inlet opening and toward said canal, the rear edge of the suction opening being bent inwardly so as to form a narrow ejector slit for the compressed air, said member being adjustably disposed and the slit being so located that the air is led past the suction opening substantially directed into the dust collecting canal, said guiding member consisting of a turning valve having a smooth guiding surface for the air and a surface so cut away toward the inwardly bent edge that the size of the ejector slit may be varied and in which the wall of the case has a continually curved internal surface.

6. A suction apparatus operating with compressed air or other fluid medium under pressure and more particularly intended for vacuum cleaners, the said apparatus comprising a case with an inlet opening of substantial width and a 30 dust collecting canal leading therefrom for the air, an opening in the said canal past which the air is led and through which dust particles et cetera are sucked and entrained into said dust collecting canal, a guiding valve member provided in the case between the last mentioned opening and the inlet opening for conducting and distributing the air from the inlet opening and toward said canal, the rear edge of the suction opening being bent inwardly so as to form a narrow ejector slit for the compressed air, said member being adjustably disposed and the slit being so located that the air is led past the suction opening substantially directed into the dust collecting canal, in which the substantially cylindrical guiding member consists of a turning valve 35 having a smooth guiding surface for the air and a surface so cut away toward the inwardly bent edge that the size of the ejector slit may be varied and in which the wall of the case has a continually curved internal surface, and in which the guiding surface of the guiding member forms with the casing a canal one dimension of which increases progressively when seen in cross section.

7. A suction apparatus operating with compressed air or other fluid medium under pressure 50 and more particularly intended for vacuum cleaners, the said apparatus comprising a case with an inlet opening of substantial width and a dust collecting canal leading therefrom for the air, an opening in the said canal past which the air is led and through which dust particles et cetera are sucked and entrained into said dust collecting canal, a guiding valve member provided in the case between the last mentioned opening and the inlet opening for conducting and distributing the air from the inlet opening and toward said canal, the rear edge of the suction opening being bent inwardly so as to form a narrow ejector slit for the compressed air, said member being adjustably disposed and the slit being 55 so located that the air is led past the suction opening substantially directed into the dust collecting canal, in which the substantially cylindrical guiding member consists of a turning valve 60 having a smooth guiding surface for the air and a surface so cut away toward the inwardly bent edge that the size of the ejector slit may be varied and in which the wall of the case has a continually curved internal surface, and in which the guiding surface of the guiding member forms with the casing a canal one dimension of which increases progressively when seen in cross section.

8. A suction apparatus operating with compressed air or other fluid medium under pressure 65 and more particularly intended for vacuum cleaners, the said apparatus comprising a case with an inlet opening of substantial width and a dust collecting canal leading therefrom for the air, an opening in the said canal past which the air is led and through which dust particles et cetera are sucked and entrained into said dust collecting canal, a guiding valve member provided in the case between the last mentioned opening and the inlet opening for conducting and distributing the air from the inlet opening and toward said canal, the rear edge of the suction opening being bent inwardly so as to form a narrow ejector slit for the compressed air, said member being adjustably disposed and the slit being 70 so located that the air is led past the suction opening substantially directed into the dust collecting canal, in which the substantially cylindrical guiding member consists of a turning valve 75 having a smooth guiding surface for the air and a surface so cut away toward the inwardly bent edge that the size of the ejector slit may be varied and in which the wall of the case has a continually curved internal surface, and in which the guiding surface of the guiding member forms with the casing a canal one dimension of which increases progressively when seen in cross section.

surface approaches the inner surface of the casting from said inlet to said outlet and a surface so cut away toward the inwardly bent edge that the size of the ejector slit may be varied and in which the wall of the case has a continually curved internal surface, and in which the guiding surface of the turning valve extends from

the central inlet opening for the air spirally toward both sides in the direction of the ejector slit so that all axial cross sections of the dimension of the air chamber are equal.
